GIUSEPPE RECONDI, OF NEW YORK, N. Y.

PRESSURE-REGULATOR.

1,063,065.

Specification of Letters Patent. Patented May 27, 1913.

Application filed November 24, 1911, Serial No. 662,252. Renewed April 18, 1913. Serial No. 762,084.

To all whom it may concern:

Be it known that I, GIUSEPPE RECONDI, a subject of the King of Italy, residing in the borough of Manhattan, city, county, and State of New York, have invented certain new and useful Improvements in Pressure-Regulators, of which the following is a full, clear, and exact description, reference being had to the accompanying drawings, forming 10 a part of this specification.

My invention relates to an improved construction of regulating valve for fluids under pressure, such as used when a fluid has to be delivered at a uniform and reduced 15 pressure from a high pressure storage tank; and has for its object to provide a valve of a simple and compact construction, carefully devised in all its minor details, with the objects in view of moderate cost of manufacture, extreme sensitiveness, and ease of regulation.

My improvements relate especially to the construction of the high pressure valve and to the arrangement of its various parts, and 25 to a special form of the spring actuating the diaphragm in opposition to the said high pressure valve.

Referring to the drawings, Figure 1 is a partly sectional view in elevation of my improved regulating valve, as applied in connection with a low pressure tank; Fig. 2 is a plan view of the same, partly sectioned; Fig. 3 is an enlarged sectional view in elevation of the high pressure valve; and Fig. 35 4 is a sectional plan view of the same.

The vessel 10 is designed to contain a gas or a liquid under a certain pressure, and may be made of any suitable shape and material. The top of the same is closed by the 40 bottom 11 of the valve casing 12, which I prefer to make, as shown in the drawings, by screwing an upper part 13 to a lower part 14 integral with or hermetically attached to said bottom part 11, which is also 45 hermetically attached to vessel 10.

The hollow space inclosed by the above mentioned parts 11, 13, 14, is divided, as usual, in two chambers 15, 16, divided by a diaphragm 17. The upper chamber, 15, 50 communicates freely with the atmosphere, and is adapted to receive the regulating spring. The lower or regulating chamber 16, however, must be hermetically sealed to prevent the escape of gas under pressure. To this end, part 14 is provided with a 55 flange or seat 18, against which is tightly

pressed at its periphery, the diaphragm 17, by means of a washer 19 held in place by the pressure exerted by screwing part 15.

Diaphragm 17 may be made of any suitable material having sufficient strength and flexibility; but I prefer to use a disk of heavy oil cloth of good quality, which I found to be adapted to give the most hermetic closure. On the spring side, this is reinforced 60 by a flexible washer of suitable material clamped between 17 and 19, which is shown in the drawings as being made out of metallic netting 20. This has the object of relieving the diaphragm of the strains set on 65 the same by the pressure in chamber 16. Inclosed within chamber 15, and actuating the diaphragm, is a regulating spring of a novel 70 and improved form, which is both inexpensive and efficient, strong and sensitive, 75 and has the additional advantage of occupying a narrow space close to the diaphragm. The same is composed of two convexed parts of sheet metal 21, 22, formed with radially extending arms 24, which may be three or 80 more in number, as desired. The said two parts are of about the same diameter, and the ends of the respective radial arms are adapted to interlock one with the other; this is obtained in a simple manner, by 85 forming one of the arms of each set with a notch 25, and the other with a tongue 26 adapted to enter the same. The upper spring plate 21 is centrally provided with a hole 27; 28 designates an adjusting screw 90 mounted through the top of part 13, having its end turned down to a pin and shoulder 29; pin 29 enters through hole 27, and the shoulder formed by the same, rests against the upper surface of spring plate 21. The 95 lower spring plate 22 rests with its central portion, preferably provided with a lug 30, against the central part of reinforcing plate 20.

The high pressure valve is composed of a 100 lower casing portion 31 secured to bottom part 11, within which are mounted the other parts.

32 is the upper portion of the casing, screwed internally to part 31, the chamber 105 thus formed being hermetically closed by means of a packing ring 33 inserted between the upper surface of 31 and the lower surface of the nut part 34 of part 32. The stem part of said part 32 is bored forming 110 a longitudinal chamber 35; the bottom of said chamber is turned as clearly shown in

Fig. 3, by forming a central projecting lug 36. The same is provided in the center with a hole 37.

38 is a high pressure valve plug formed with a head 39 and a stem part 40, the diameter of which is just a trifle, almost unnoticeably smaller than the diameter of hole 37.

The arrangement just described for the inlet of fluids at a high pressure within the low pressure chamber, is an important factor in the regularity of operation of my device. In similar devices, the valve plunger is usually caused to close an opening against which it is held by the pressure of a spring; when the pressure decreases in the low pressure chamber, said plunger is operated by the diaphragm and detached from its seat, allowing the free access of the gas under high pressure to the opening thus uncovered. The area of the uncovered section is not uniform in all cases, but is larger or smaller according to the more or less decrease in pressure of the low pressure chamber; it is in all cases considerably larger than in my device, where no free area is open to the inrush of gas, but only a small clearance obtained by a slight difference of diameter between the inlet to the low pressure chamber and the plug filling the same. Moreover, the section through which the gas is allowed to pass, is uniform in all cases, so that the gas is always fed to the low pressure chamber in a gradual manner, preventing the sudden disturbances in pressure conditions within the same which usually result in connection with other devices.

41 is a hollow plunger adapted to fit longitudinally within chamber 35, leaving however some clearances between its outer surface and the surface of chamber 35. A convenient construction is that shown in the drawings; Fig. 4, in which part 41 is shown with a polygonal outline, the diameter of the inclosing circle being the same as the diameter of chamber 35. Thus between the faces 42 of part 41, and the surface 43 of chamber 35 will be formed chambers or clearances 44 when the several parts are assembled. Chamber 45 internal to part 41 has a bottom part 46; externally to this, or in other words on the top of part 41, is provided a rim 47 forming a recess 48, and in this is inserted a disk 49, preferably of leather.

During the process of manufacture, the lower edge of part 32 is turned down, thus forming a very thin wall around the opening of chamber 35. In this chamber are then inserted hollow plunger 41, a compression spring 50 holding the same against lug 36; an extremely fine metal gauze disk 51, and a washer 52 provided with a hole or holes 53. The lower edge of part 32 is then bent inward, forming the flange 54 retain-

ing the different parts mentioned permanently assembled.

55 designates a pipe attached in 56 to part 31, and leading the fluid under pressure from the storage tank or other source of supply, to the chamber formed by parts 31, 32.

57 is a pipe establishing a direct communication between regulating chamber 16 and the interior of vessel 10. The same is preferably bent as shown, so as to direct the stream of the fluid under pressure coming from chamber 16 against the bottom of part 31. I have found that by so doing the action of the valve is more regular and sensitive, probably because the force of the current is smoothed down, and the fluid is evenly distributed on all sides.

The action of this device is as follows: The spring formed by parts 21 22 having been adjusted by means of screw 28 for a certain pressure, if the pressure of the fluid contained in vessel 10 and in the chamber 16 communicating therewith is sufficient to counterbalance by its action against the diaphragm 17 the action of the spring, the different parts will be in the relative positions shown in the drawings. Spring 50 acting against bottom 46 will force disk 49 against lug 36, closing hole 37. Disk 49 being of leather or other soft material, acts in this respect most effectively, and has the considerable advantage over the usual type of conical valve of not requiring any special accuracy in manufacturing.

When the pressure of the fluid contained in vessel 10 and chamber 16 decreases, the plate spring pushes the diaphragm against the head 39 of plug 38 in opposition to the pressure of spring 50. When the difference between the two pressures, that exerted by the fluid in chamber 16 against the diaphragm, and that exerted by the plate spring against the diaphragm and the plug 38 becomes greater than the pressure exerted against said plug 38 by spring 50 acting against part 41, plug 38 forces down part 41, and the fluid under high pressure coming from pipe 55 is therefore allowed to enter hole 37 passing through hole 53, metal gauze 51 and clearances 44. As stated, said metal gauze is exceedingly fine, and acts as a filter to prevent the entrance of any solid particle within the high pressure valve chamber, to insure the correct working of plug 38 and to prevent the plugging of the clearance existing between said plug and the wall of hole 37.

The slightest difference in diameter between the hole and the plug is more than sufficient for permitting the passage of the gas under pressure; in fact I have noticed that the smaller the difference the better the results, any tendency to retard the inrush of the fluid from the high pressure

chamber to the low pressure chamber, being beneficial in improving the regularity of operation and the sensitiveness of the device.

5 Some regulating valves designed for the same purpose as the one just described, have the high pressure piston directly connected to the diaphragm; this is one point that I was careful to avoid in the construction of 10 my improved device, since, as I have stated, it is essential that the diaphragm be absolutely hermetical, and it is extremely difficult to maintain this hermeticity in a moving diaphragm perforated to receive a valve 15 stem connected to it.

From the foregoing it will be seen that I provide a simple arrangement of parts inexpensive to manufacture, all easily accessible for the purpose of repairs, and the 20 highly satisfactory working of which is due solely to the careful study of their various details and not to any special care required in manufacturing.

It may be here noted that the washer 19 is preferably made tapering toward the inside, so as to clamp parts 20 and 17 with only a narrow circular surface or edge, rather than with a wide surface; this insures a better clamping action.

30 I have found this pressure regulating valve to be very sensitive and regular in its action, and therefore eminently suitable for those uses where these two factors are important, like for instance in connection with 35 tanks for delivering liquid or gaseous fuel to burners connected with the same, and especially when said burners are used for lighting purposes and the steadiness of the flame is all important.

40 Having thus described my invention, what I claim as new, and desire to secure by Letters Patent of the United States is:

1. In a device of the character described, and in combination with a high pressure 45 and a low pressure chamber, a regulating valve comprising a hollow casing connected to the high pressure chamber, a hollow closing member secured to the same provided with an inwardly projecting lug having an 50 opening connecting the inside of said casing with the low pressure chamber, a hollow plunger movable within said hollow member, a wire screen filtering the fluid fed to said valve previous to its entering said 55 hollow closing member, a spring within said plunger controlling the same, a washer of plastic material retained by said plunger against said lug closing said opening, a longitudinally movable plug inserted through 60 said opening and resting against said plunger having a section area a trifle smaller

than the area of said opening, and a diaphragm controlling said plug retaining the same in position; substantially as described, and for the purposes as set forth. 65

2. The combination of a body, having an inwardly projecting flange, a diaphragm on said flange, a flexible backing member for the same, a hollow cover secured to said body clamping said diaphragm and backing member against said flange, a compression spring between said cover and said backing member, a hollow valve casing secured to the bottom of said body having an opening connecting the same internally to 75 said body, a plunger closing said opening, means for holding said plunger against said opening, and a longitudinally movable plug inserted through said opening and held against said plunger by the action of said 80 diaphragm, having a section area a trifle smaller than the area of said opening; substantially as described, and for the purposes as set forth.

3. The combination of a body, having an 85 inwardly projecting flange, a diaphragm on said flange, a flexible backing member for the same, a hollow cover secured to said body clamping said diaphragm and backing member against said flange, a spring 90 composed of two convex metal plates having radial arms interlocking with each other between said cover and said backing member, a screw through said cover adjusting the pressure of said spring, a hollow valve casing secured to the bottom of said body connected to the high pressure fluid supply, a hollow closing member secured to the same provided with an inwardly projecting lug having an opening connecting the inside 95 of said casing with the inside of said body, a hollow plunger movable within said hollow member, a wire screen filtering the fluid fed to said valve previous to its entering said hollow closing member, a spring within 100 said plunger controlling the same, a washer of plastic material retained by said plunger against said lug closing said opening, a longitudinally movable plug inserted through said opening and held 105 against said plunger by said diaphragm having a section area a trifle smaller than the area of said opening, and a pipe attached to the bottom of said body conveying the fluid fed thereto against the bottom 110 of said valve casing; substantially as described, and for the purposes as set forth.
